US0D1031514S

(12) **United States Design Patent** (10) **Patent No.:** **US D1,031,514 S**
(45) **Date of Patent:** **** Jun. 18, 2024**

(54) **PERSONAL MOBILITY**

(71) Applicants: **Hyundai Motor Company**, Seoul (KR); **Kia Corporation**, Seoul (KR)

(72) Inventors: **Joon Ho Lee**, Seoul (KR); **Seung Wook Ryu**, Seoul (KR)

(73) Assignees: **Hyundai Motor Company**, Seoul (KR); **Kia Corporation**, Seoul (KR)

(**) Term: **15 Years**

(21) Appl. No.: **29/831,233**

(22) Filed: **Mar. 18, 2022**

(30) **Foreign Application Priority Data**

Dec. 22, 2021 (KR) 30-2021-0061805
